UNITED STATES PATENT OFFICE.

ARTHUR BECK AND CHARLES BECK, OF ST. LOUIS, MISSOURI, ASSIGNEES, BY MESNE ASSIGNMENTS, TO SAFETY APPLIANCE COMPANY, OF ST. LOUIS, MISSOURI, A CORPORATION OF MISSOURI.

DOOR-CONTROLLED ELEVATOR SYSTEM.

1,175,220.

Specification of Letters Patent. Patented Mar. 14, 1916.

Application filed March 5, 1914. Serial No. 822,645.

To all whom it may concern:

Be it known that we, ARTHUR BECK and CHARLES BECK, citizens of the United States, residing at St. Louis, State of Missouri, have invented certain new and useful Improvements in Door-Controlled Elevator Systems, of which the following is a full, clear, and exact description, reference being had to the accompanying drawings, 10 forming a part hereof.

Our invention has relation to improvements in door-controlled elevator systems; and it consists in the novel features of construction more fully set forth in the specification and pointed out in the claims.

In the drawings, Figure 1 is a diagrammatic view of an electric elevator system with the several devices and wiring shown more or less conventionally and our invention 20 applied thereto; Fig. 2 is a side elevation of the safety switch to which our invention is in the main, directed; Fig. 3 is a front elevation thereof; Fig. 4 is a detached face elevational view of the oscillating contact 25 lever of said switch, which directly controls the annunciator or light circuit; Fig. 5 is a top plan of Fig. 4; Fig. 6 is a cross-section on the line 6—6 of Fig. 4; Fig. 7 is an enlarged vertical cross-section on the line 7—7 30 of Fig. 3 showing the buffer for the plunger armature of the safety switch; and Fig. 8 is a diagrammatic view showing the series arrangement of the gate contacts.

The object of our invention is to provide 35 an automatic switch mechanism for electric elevators (or equivalent hoisting apparatus) which will depend for its operation on the closing and opening of the gate at any floor or landing at which the passengers 40 (or freight) in the car are to be discharged, or at which they are to enter the car. The door switches are in circuit with the motor by which the car is hoisted or lowered, the motor circuit being open (or broken) with 45 the opening of any door of the elevator shaft (the door switches being connected in series) so that the operator can not under the circumstances start the car. At the same time, the plunger armature of the switch to 50 which our invention is directed, controls the closing and opening of suitable annunciator or lighting circuits whereby the operator in the car can tell at a glance whether the motor circuit is closed or open, depending

either on the nature of the sound of the 55 annunciator or on the color of the signal light, and being so guided, the operator is in position to know whether the coast is clear to start the car.

A further object of our invention is to 60 provide a switch with yielding electrodes or wipers of special design to prevent arcing and sparking with the separation of the circuit-closing terminals of said electrodes; and further, to provide a system possessing 65 advantages better apparent from a detailed description of the invention, which is as follows:

Referring to the drawings, and for the present to Figs. 1 to 7 inclusive, M, represents an electric motor provided with a separately excited field F, the motor having coupled thereto a drum D over which winds a hoisting cable c passing over pulleys P, P', at the top of the elevator shaft H, the upper 70 end of the cable having suspended therefrom the car or cage C, all as fully understood in the art. In front of the car, at each floor or landing operates the sliding gate G, (only one floor being shown in the illustration) for admitting passengers (or freight or both) into, and discharging them from, the car, the top of the gate being provided with an arm 1 to the free outer end of which is secured a yielding contact wiper 75 2, said arm 1 and wiper 2 constituting a door switch. With the closing of the gate said wiper 2 passes between and engages the spring contacts 3, 3, mounted in a contact box 4 secured along the wall of the shaft in 80 the path of the arm 1, said contacts having secured to them within the box the terminals of the wires 5, 6, identified with the coil-energizing sections of the motor-circuit. The line wires L, L' constitute the immediate 85 source of electric energy, the wire 5 leading to the wire L through a wire 5', and the wire 6 reaching the wire L' through the wire 6', the wires 5', 6', being but mere extensions of the wires 5, 6, respectively. 90 100

It will be seen from the foregoing that a closing of the gate G will close the circuit comprising the elements L, 5', 5, 3, 2, 3, 6, 6' L'. In the path of the wire 5 is interposed a solenoid s provided with a reciprocating plunger armature or core t, constituting a safety-switch, the closing of the aforesaid coil-energizing circuit (L, 5', 5, 3 105

2, 3, 6, 6', L'), hereinafter to be designated as the safety circuit, having the effect of energizing the solenoid *s* and thus lifting (or moving) the member *t* sufficiently to bring its ends into engagement with the contacts *a*, *a'* terminating the wires 7, 8, respectively, the former of which constitutes one of the terminals of the switch solenoid 9 mounted on the switch-board R, the wire 8 on the other hand leading from the contact *m* adjacent to which is a similar contact *m'* forming the terminal of a wire 10 which leads from the wire 5, the wires 8, 10, being connected by a resistance *r* as shown. The opposite terminal of the solenoid 9 is formed by a wire 11 which branches from the wire 5. The plunger armature 12 of the solenoid 9 is provided with a bottom terminal link 13 suspended from a pin 14 and spaced from the plunger by a thimble 15' passed over the pin (Fig. 2), the link 13 in turn supporting an oscillating lever 15 secured by a pin or stud 14', the lever being provided with a fulcrum pin 16 on the slab or switch-board R, the short arm of the lever being provided with spring-controlled wiper plugs or contacts 17, 17', coöperating respectively with the contacts *m*, *m'*. Each plug or wiper 17, 17', is controlled by a spring *h* confined in a socket *e* in the member constituting the short lever arm of the lever 15. Before energization of the solenoid 9 takes place, the plunger 12 occupies its lowest position so that the short lever-arm of the lever 15 points upward (Fig. 3) the wipers 17, 17' being in engagement with their respective contacts *m*, *m'*. Now, when the gate G closes so as to close the circuit L, 5', 5, 3, 2, 3, 6, 6' L', the solenoid *s* of the safety-switch becomes energized so as to move the member *t* into engagement with the contacts *a*, *a'*. This accomplished, a portion of the current will traverse the following circuit: From wire L through wires 5', 5, 11, through solenoid 9, thence through wire 7, contact *a*, plunger *t*, contact *a'*, wire 8, contacts *m*, *m'* by way of the short lever-arm of lever 15, wires 10, 5, contacts 3, 2, 3, wires 6, 6' back to wire L', the resistance *r* being short-circuited. The circuit just traced constitutes the main switch circuit, the current traversing the solenoid 9 energizing the latter whereupon the plunger armature 12 is lifted (see dotted position Fig. 3), pulling the lever 15 after it, which is thus oscillated upwardly about its fulcrum 16, and causing the separation of the contacts *m'*, 17', and *m*, 17, respectively. The instant however that the circuit between the contacts *m*, *m'* is broken, the current simply passes through the resistance *r*, the purpose of the latter being to reduce the current strength through the solenoid 9 and prevent heating the coil thereof once the plunger 12 has been lifted to a point approaching its upper limit, at

which point the current may well be reduced as the plunger has but a short distance to travel to complete its full upward stroke.

The solenoid 9 above referred to, forms an element of the safety-switch to which our invention is in the main directed. The safety-switch comprises in addition to the parts above described, a slate or equivalent non-conducting platform 18 mounted at the upper end of the plunger 12, said platform 75 having disposed at opposite sides thereof the angle contact plates 19, 19, overhanging the edges of the platform, the vertical leg of each plate being adapted to engage a pair of spring-controlled or yielding wipers 20, 20' depending from a corresponding pair of superposed conducting posts 21, 21' mounted on the board R, the post 21' overhanging the post 21 and being of angle form so as to bring its wipers 20' in line with the 80 wiper 20, whereby each pair of wipers may simultaneously engage its plate 19. Each post or bracket (21, 21') is provided with a shock-absorber or buffer in the shape of a plunger or pin 22 whose upper terminal head engages 85 the bottom of the free end of a flexed spring 23 having its fixed end secured to the post. The lower end of the plunger projects normally below the bottom of the post and as the same is impinged by the rising platform 18, the shock is communicated through the members 22 to the springs 23 which thus absorb the shock and thus act as buffers. Leading from the posts 21' (the connections being always made on the back of the board 90 R as well understood in the art) are conducting wires 24, 25 respectively, the same leading to contacts *n*, *n'* operating in connection with a conventional oscillating hand switch S. The arms of said switch are in 100 electric connection with the wires 26, 27 leading respectively to the field F, and to one of the contacts in the operator's switch O in the elevator car C. Leading also from the said switch O are wires 28, 29, the first 105 being connected to a solenoid 30, whereas the other wire 29 is connected to a corresponding solenoid 30', a wire 31 connecting the solenoids. These solenoids constitute the 110 energizing coils of the oscillating reversing switches 32, 32' respectively, mounted on the board R', the arms of the switch 32 coöperating with the contacts *b*, *b'*, and the arms of the switch 32' coöperating with the contacts *d*, *d'*. The switches are shown conventionally herein and their action is well understood by those skilled in the art. In electric connection with the wire 27 is a wire 27' which like the wire 26, leads to the field F. Connecting the pivotal points of corresponding arms of the switches 32, 32', is a wire 33 which (together with the wire 31) is in electric connection with the pivotal point of one of the arms of the switch S through a wire 34. From the pivot of the opposite arm of 115

the switch S leads a wire 35 to the second arm of the switch 32'; and from the corresponding arm of the switch 32 leads a wire 36 to the wire 35. From the contact b leads 5 a wire 37 to the motor M; and from the contact b' likewise leads a wire 38 to the motor M.

From the foregoing it is apparent that if the gate G is closed, thereby closing the 10 safety circuit (or the circuit to the closing of which the plunger armature 12 responds to lift the lever 15) the car C can still not be started until the switch-lever W (connected electrically to the wire 27) is thrown 15 by the operator in proper direction to bring one or the other of the wires 28, 29 into circuit with the wire 27. Let us assume that the switch S has been swung to operative position and that the lever W has been 20 swung to the left from its intermediate or cut off position (Fig. 1) whereby the wires 27 and 28 are brought into circuit. The gate G being closed, it follows that the solenoid 9 will be energized, the plunger 12 25 lifted, and the plates 19, 19 brought into engagement with the wipers 20, 20' of the posts 21, 21' and thus brought into electric connection with their respective wires 5', 6', 24, 25, whereby a portion of the line current will be conducted (in parallel) to the 30 knife-switch S, and thence to the motor F; the path of flow of the current (after traversing the wires L and 5') being from one of the posts 21 across one of the plates 19 35 to the opposite post 21' (see arrow Fig. 2), thence through said post 21', wire 25, the adjacent arm of the switch S, a short section of wire 27, wire 27', field F, wire 26, the opposite arm of the switch S, wire 24, 40 the second post 21', through its corresponding contact-plate 19, through the second post 21, and finally through wire 6' to line L'. This circuit thus conducted in parallel 45 from the main line will for convenience be hereinafter referred to as the main motor circuit, the field circuit of the motor, comprising the elements 27, 27', F, 26, being closed when the switch S is closed. The lever W of the operator's switch O having 50 been thrown to the left (as previously assumed to be the case), results in the energization of the solenoid of one (32) of the reversing switches (32, 32'), a local circuit being set up which for convenience may be 55 termed the reversing switch controlling circuit, said circuit under the circumstances being substantially as follows, it being convenient to start with the wire 34 at the base of the left arm of the switch S. Through 60 wire 34, to the left along wire 31, through solenoid 30, wire 28 to switch O, thence from said switch through wire 27 back to the base of the adjacent right-hand arm of the switch S. The energization of the solenoid 30 closes the switch 32 and there then

sets up a motor armature circuit which drives the car C in one direction, said circuit being substantially as follows: Beginning with the wire 34 it passes through wire 33 to the left, through right arm of switch 70 32, contact b', wire 38, motor M (upwardly, Fig. 1), wire 37, contact b, left arm of switch 32, wire 36, and wire 35 to the switch S. Suppose on the other hand that the switch-lever W is thrown to the right so as 75 to connect wires 27, 29. In that case the car will be driven in an opposite direction, the reversing switch-controlling circuit being as follows: From wire 34, to the right along wire 31, solenoid 30', wire 29, switch 80 O, wire 27, back to the switch S. The motor armature circuit will now be in a reverse direction and is substantially as follows: From wire 34, to the right through wire 33, right hand arm of switch 32', contact d', short wire 37', wire 37, motor M (downwardly, Fig. 1) wire 38, short wire 38', contact d, left-hand arm of switch 32', wire 35, back to the switch S.

In the practice of our invention there is 90 brought into service still another circuit, to wit, the signal or annunciator circuit, the current for which is supplied from the line wires E, E'. The purpose of the annunciator is to put the operator on guard in starting his car; and in the present embodiment of our invention we employ a red light as the danger signal, and a green light as the safety signal. This circuit is controlled directly by the lever 15 as will more fully 100 hereinafter appear. The arrangement here employed is substantially as follows: Leading from the line wire E is a wire 39 which is in electric connection with a flexed spring wiper or contact 40 on the board R, a second wiper or contact 40' adjacent thereto having 105 leading therefrom a wire 41 connecting with one pole of the lighting filament of a green (or other color) safety signal-light 42 in the car, the opposite pole of the filament being connected by a wire 43 with a wire 44 connecting respectively with the line wire E' and with one pole of the lighting filament of the red or danger light 42', the opposite 110 pole whereof is connected by a wire 45 with a bottom spring wiper or contact 46 (on the board R) an adjacent contact or wiper 46' being connected by a wire 47 with the wire 39.

The free end of the long arm of the lever 120 15 is weighted by an I-block 48, the web whereof is protected by an insulating member 49 (spanning the block) one end of which is screwed to the lever 15. The flanges of the I serve as electric conductors or contacts as quite obvious from the drawing. When the gate G stands open, the solenoid 9 not being energized, it follows 125 that the plunger 12 will be in its lowest position and the contact 48 carried by the 130

long arm of the lever 15 (which may be termed as the signal controlling lever) will be in engagement with the contacts 46, 46' (Fig. 1). In that case the light circuit will 5 include the following elements: The current passes from the wire E, through wire 39, wire 47, contact 46', the lower flange of the I 48, contact 46, wire 45, light 42', wire 44, and back to the line wire E'. The red (or 10 other) light thus notifies the operator not to start his car, the danger light (or equivalent signal) informing him that either there is a short circuit somewhere on the line, or that one or more of the gates G is open. 15 When, however the gates are closed, the solenoid 9 becomes energized, the lever 15 is lifted, the contacts between the members m m', 17, 17' broken, and the upper flange of the I 48 is brought into engagement with 20 the upper pair of wipers 40, 40' (see dotted position Fig. 3), whereupon the course of the light circuit is as follows: From line E, through wire 39, wiper 40, upper flange of the I 48, wiper 40', wire 41, safety light 42, 25 wire 43, wire 44, back to the line wire E'. The operator thus knows that all danger is over and he is free to start his car by a throwing of the switch lever W in proper direction. Any form of light signal, or 30 annunciator or alarm device is contemplated by our invention.

Where there are several floors or landings, the contacts 3, 3, are wired in series (Fig. 8) so that when any gate of the series is closed 35 or open (irrespective of the position of the car) the operator in the car can tell from the color of his signal light just what has happened. No attempt is here made to show the wiring of the car to illustrate how 40 the wires lead to the lights in the car with any position of the car, as these matters are well understood in the art. Features illustrated but not alluded to are likewise well understood and a description thereof is here 45 unnecessary.

The contacts 19, 20, 20' serve to distribute the current over a large area and when the plates 19, 19 separate from the spring wipers 20, 20', there is practically no arcing 50 or sparking at the moment of separation. Obviously, the invention is applicable to any form of hoisting apparatus. It may be convenient in passing to state the specific object 55 of the safety-switch s, t. Should for example the wire 8, or any wire identified with the solenoid 9 become grounded, or otherwise short-circuited, that circumstance will tend to keep the plunger 12 with its platform 18 and plates 19, 19 in their raised 60 position (the grounded or short-circuited current tending to keep the coil 9 energized). This grounding or short-circuiting, however, if of a character as to allow undue leakage of the current, will so reduce the voltage 65 through the solenoid s as to prevent energi-

zation of the same and thus allow the plunger armature t to drop away from its contacts a, a'. When this happens the circuit to the solenoid 9 is broken and the latter can not become energized until the defect is corrected. The safety-switch s, t, thus serves to break the motor-circuit in the event the gate G is opened and the solenoid 9 is accidentally grounded or short-circuited. For it must be obvious that with the opening of the gate, the deenergization of the solenoid 9 should instantly follow, and were it not for the safety-switch s, t, the energization of the solenoid would continue even after the gate was opened, which is the very 75 thing to be avoided, not only for the reason that it is desirable that the plunger 12 should instantly respond to the closing and opening movements of the gate, but that the operator shall have the proper signal on 80 the car.

Having described our invention, what we claim is:

1. In combination with a car, an electric motor for impelling the same, a source of electric energy, a safety circuit leading from said source, a safety-switch in the path of said circuit, a gate opposite the car for closing said safety circuit with the closing of the gate, a main-switch circuit, a solenoid forming a part of said switch circuit, a main motor circuit adapted to be closed with the energization of the solenoid upon the closing of the gate, a movable member responsive to the current traversing the solenoid, and an annunciator or signal circuit controlled by said movable member. 95

2. In combination with a car, an electric motor for impelling the same, a source of electric energy, a safety circuit leading from said source, a gate opposite the car for closing said safety circuit with the closing of the gate, a main switch circuit, a solenoid forming a part of said switch circuit, a motor circuit adapted to be closed with the energization of the solenoid upon the closing of the gate, a plunger-armature in the solenoid responsive to the current traversing the solenoid, and an annunciator or signal circuit controlled by said armature. 105

3. In combination with a car, an electric motor for driving the same, a source of electric energy, a safety circuit leading therefrom, a gate opposite the car for closing said circuit with the closing of the gate, a main switch circuit, a solenoid forming a part of said circuit, a plunger-armature for the solenoid, a main switch mounted on the armature, a motor circuit leading from the main switch and terminating in a plurality of wipers for engaging the switch aforesaid, whereby the motor circuit is connected in parallel with the main switch circuit with a closing of the gate and consequent energization of the solenoid, suitable signal circuit. 110

- cuits, and a device on the plunger armature for controlling said signal circuits.
4. In combination with a car, an electric motor for driving the same, a source of electric energy, a safety circuit leading therefrom, a gate opposite the car for closing said safety circuit with the closing of the gate, a main switch circuit, a solenoid forming a part of said circuit, a plunger armature for the solenoid, contact plates carried by and insulated from the armature, a motor circuit in parallel with the main switch circuit and terminating in a plurality of wipers for receiving between them the contact plates aforesaid, a buffer or shock absorber operative with a movement of the armature in one direction, suitable signal circuits, and a device on the plunger armature for controlling said signal circuits.
5. In combination with an elevator gate, an electric motor, a main switch, a main switch circuit adapted to be closed with a closing of the gate, an energizing coil traversed by said circuit, a motor circuit leading from the main switch, an armature actuated by the energization of said coil and operating to connect in parallel the motor circuit and the main switch circuit, a signal circuit, and contact devices operating in conjunction with said signal circuit and adapted to be actuated by a movement of the armature.
6. In combination with an elevator cage and gate, a safety circuit adapted to be closed with the closing of the gate, a main switch, a solenoid-operated safety switch in the path of said safety circuit, a main switch circuit, a solenoid in the path of said circuit, a motor, a motor circuit leading from the main switch, a plunger armature actuated by the energization of the solenoid and operating to connect in parallel the motor circuit and the main switch circuit, a signal circuit traversing the cage, and contact devices operating in conjunction with the signal circuit and actuated by the movement of the armature in one direction.
7. In combination with an elevator gate, a safety circuit adapted to be closed with the closing of the gate, a main switch, a main switch circuit, a solenoid in the path of said circuit, a motor, a motor circuit leading from the main switch, a plunger armature for said solenoid, a pair of insulated conducting plates carried by the armature, wipers arranged in pairs for receiving between them the conducting plates aforesaid, one member of each pair being in the path of the main switch circuit and the other members being in the path of the motor circuit, whereby the latter circuit becomes connected in parallel to the main switch circuit, a signal circuit, lights in said signal circuit, an oscillating lever actuated by the plunger armature, suitable contacts or wipers arranged in pairs on opposite sides of the lever aforesaid, and a conducting member on the lever for alternately engaging said contacts with the closing and opening movements of the gate.
8. In combination with an elevator gate, a source of electric energy, an electric motor, a main switch, a main switch circuit adapted to be closed with a closing of the gate, an energizing coil traversed by said circuit, a motor circuit leading from the main switch, and an armature actuated by the energization of said coil and operating to connect in parallel the motor circuit and the main switch circuit.
9. In a door-controlled elevator system, a source of electric energy, a car, a door opposite the car, a main switch, a main switch circuit adapted to be closed with a closing of the door, a motor, a coil in the path of the main switch circuit, a plunger armature for said coil, a motor circuit leading from the main switch and adapted to be closed by the armature upon a movement of the latter with an energization of the coil, a field winding for the motor adapted to be energized with a closing of the motor circuit, an operator's switch in the car, a reversing switch, a controlling circuit between said reversing switch and operator's switch, a motor armature circuit between the motor and reversing switch, a signal circuit, and means actuated by the plunger-armature in the coil of the main switch circuit for controlling the signal circuit.
10. In combination with an elevator cage and gate therefor, a main switch circuit adapted to be closed with a closing of the gate, a coil in the path of said circuit, a main switch, a motor, a motor circuit leading from the main switch, a plunger-armature actuated by the energization of the coil and adapted to connect in parallel the motor circuit and the main switch circuit, a signal circuit traversing the cage, circuit closing devices operating in conjunction with the signal circuit and actuated by the movement of the armature in a given direction, an operator's switch in the car, a reversing switch, a controlling circuit between said reversing switch and operator's switch, and a motor armature circuit between the motor and reversing switch, the parts operating as set forth.

In testimony whereof we affix our signatures, in presence of two witnesses.
